UNITED STATES PATENT OFFICE.

WILLIAM R. GLASGOW, OF ST. LOUIS, MISSOURI.

MACHINE FOR HANDLING MATERIALS.

Application filed October 19, 1923. Serial No. 669,541.

This invention relates to loading machines, such as may be used for gathering loose materials and loading the same on conveyances for removal, and to machines of similar character.

One of the objects of this invention is to provide a power operated machine by which a load of material, such as earth, gravel and the like, may be gathered and elevated for transportation or for depositing in a conveyance for transportation.

Another object of this invention is to provide a machine by means of which such a load may be elevated to a sufficient height to be deposited in a conveyance having an elevated body.

Another object of this invention is to provide such a device by which the load may be not only lifted, but swung to either side for depositing in a conveyance.

Another object of this invention is to provide a machine by which these various operations may be carried out and which may be driven and operated by a single operator.

Another object of this invention is to provide such a device which may be applied to a power vehicle of standard construction.

Further objects will appear from the detail description taken in connection with the accompanying drawings, in which:

Figure 1 is a side elevation, partly in section, of a machine embodying this invention;

Figure 2 is a plan view of the same; and Figure 3 is a detail sectional view of the arrangements for swinging the load.

Referring to the accompanying drawing, 1 designates a power propelled frame provided with traction wheels 2 and steering wheels 3. This may take the form of an ordinary tractor of any suitable design. The embodiment illustrated in the drawings is shown as applied to a tractor of what is known as the Fordson type.

Mounted on the front of the frame 1 is a suitable bracket 4 upon which is mounted an upright column 5 suitably braced by means of braces 6 so as to maintain the same in upright position. The column 5 has an internal section 7 mounted for rotary and vertical sliding movement in the section 5 and forming therewith a telescoping column adapted to be extended upwardly so as to increase the normal height of lift. The

section 7 is provided at its upper end with a horizontally extending boom 8 which may be elevated by elevating the section 7 and which may be swung laterally by rotating the section 7. The column 5—7 as well as the boom 8 may be formed of hollow pipe and the boom has suspended therefrom by means of cables 9 and 10, a bucket or shovel 11.

Mounted on a bracket 12 fixed within the lower end of the section 5 is an upright hollow column or post 13 carrying at its top a flange 14 fitting within the section 7 and adapted to act as a guide therefor. The cables 9 and 10 each have one end anchored to the boom 8 and pass downwardly over a pair of sheaves 15 on the shovel 11, then upwardly to the boom 8 passing through openings in the pipe to the interior thereof, then over a pair of sheaves 16 mounted in the boom 8 to a pair of sheaves 17, only one of which is shown, to the interior of the column 5—7. Within the columns the cables pass downwardly around a pair of sheaves 18 fixed within the lower end of the section 7, thence upwardly and around a pair of sheaves 19 mounted on the flange 14, thence downwardly through the interior of the post 13 and around a pair of sheaves 20 to the outside of the column 5. Only one of each of the sheaves 18, 19 and 20 is shown in the drawings so as to avoid confusion. After passing out of the column 5, the cables pass upwardly between said column and the front of the tractor frame to a pair of sheaves 21, each mounted on the end of one of a pair of levers 22 and thence over a pair of sheaves 23 mounted on the opposite ends of said levers. After passing over the sheaves 23, the cables pass downwardly to a winding drum 24 mounted on the side of the frame 1. The ends of both cables are fixed to the drum 24 and the cables are wound thereon simultaneously so that, considering for the moment that all the sheaves over which the cables pass are stationary, the shovel 11 will be lifted by both cables alike as they are wound up by the drum 24.

The drum 24 is connected by means of a suitable clutch and brake device 25 of any well known construction to a worm gear driven by a shaft 27 operated by the power plant of the vehicle in any well known manner. The clutch and brake device 25 may be operated by means of a suitable control

lever 28 so that as soon as the clutch connects the drum for driving engagement, the brake is released and vice versa.

Mounted on the boom 8 and below the same is a bracket 29 carrying a half round bar 30 extending crosswise of the boom. The shovel 11 is provided with a pair of channels 31 extending from front to rear thereof and adapted to engage the cross-bar 30 when the shovel has been elevated to a sufficient height.

The section 7 is free to move vertically within the section 5, while the post 13 is stationary. It will be clear, therefore, that when the shovel 11 has been elevated until the abutments 31 engage the cross-bar 30, if the drum 24 continues winding, the tension of the cables acting through the sheaves 18 and 19 will cause the section 7 to be lifted vertically in the section 5. This vertical movement may continue until arrested by a suitable stop as will be hereinafter described.

In order to provide for rotating the section 7, a collar 32 is secured by means of screws 33 to the upper end of the column 5. The collar 32 is provided with an over-turned edge 34 taking over a ring 35 mounted loosely on the upper end of the column 5 and having secured thereto a bevel gear 36. The ring 35 is loosely confined between the upper edge of the column 5 and the over-turned edge 34 of the collar 32 so as to be rotatable on the upper end of the column. The ring 35 is provided with inwardly extending and diametrically opposite lugs 37, each adapted to work in a slot 38 in the section 7. A bevel gear 39 adapted to mesh with the gear 36 is journaled in a bracket 40 mounted on the bracing 6 and connected by means of a universal joint 41 with a control rod 42 provided with an operating hand wheel 43 for manipulation by the driver. When the section 7 is lifted vertically by the operation of the cables, the lugs 37 ride in the slots 38 but when the gear 39 is operated, the ring 35 will be rotated and by engagement of the lugs 37 will rotate the section 7 so as to swing the boom 8 to one side or the other. The operator is thus able to lift the load to any desired height and then swing the shovel laterally so as to dump the load into a high bodied conveyance standing alongside of the machine. The ends of the slots 38, acting against the lugs 37, provide to limit the lift of the section 7.

The levers 22 are pivoted at the common axle of the two sheaves 23 on a bracket 44 mounted on the bracing 6. The other ends of these levers are hung each on one end of a cable 45 which passes from the end of one lever 22 up over one of a pair of sheaves 46, then downwardly to a drum 47 mounted on a bracket on the bracing 6 and to which the middle of the cable is fastened, thence back over the other sheave 46 and to the other

lever 22. Thus the cable 45 has its middle point fixed to the drum 47 and its two ends supporting the two levers 22.

It will be clear that by rotating the drum 47 by means of a manipulative hand wheel 48, one of the levers 22 will be elevated and the other lowered an equal amount. This will have the effect of correspondingly taking up one and slackening off the other of the cables 9 and 10. It will also be clear that since both levers 22 are pivoted on a common pivot and are moved equally by the operation of the drum 47, the effective lengthening of one of the cables 9 and 10 will be equal to the corresponding shortening of the other. The effect of this lengthening and shortening will be to tip the shovel 11 so that the same may either be tipped back so as to carry the load without spilling, or tipped forwardly so as to dump the load. Furthermore since the cross-bar 30 is round on the bottom, the channels 31 when in contact therewith may rock about said cross-bar as the cables 9 and 10 are lengthened or shortened so that the shovel 11 may be adjusted or tipped either when hanging free or when in engagement with the abutment 30. The hand-wheel 48 may be equipped with a brake 49 releasable by a suitable handle 50 so that when the shovel has once been adjusted for position, it may be held in that position.

In the operation of this device the operator may lower the shovel 11 to position for gathering up the load and then drive the tractor forward so as to shovel up the material. An abutment 51 on the bucket is adapted for suitable engagement with the front of the bracket 4 or other suitable part of the device so as to propel the shovel for filling the same. After filling the shovel, the drum 47 may be operated so as to tip the front end upwardly in order to carry the load without spilling. If now the load is merely to be transported and dumped in another locality, the shovel may be elevated to any position above the ground and the tractor may then be propelled so as to transport the load. After arriving at its destination, the load may be dumped by operating the drum 47 to tip the shovel forwardly. If on the other hand the machine is being used for loading carts or other conveyances, such a cart may be drawn up along side of the machine. In this case the shovel may be elevated until the channels 31 engage the abutment 30 and then if necessary the column 5-7 may be extended through the operation of the cables 9 and 10 by simply continuing to wind up on the drum 24. When the required elevation has been obtained, the hand-wheel 43 may be operated to rotate the section 7 and swing the boom with its load laterally over the conveyance to receive the load. The bucket may then

be tipped as above described so as to dump the load into such conveyance. If it is desired to use the machine for excavation, the shovel may be lowered to the ground with the point tipped forwardly, and then propelled forwardly by operating the tractor. The load may then be elevated and dumped as described above. In this service suitable bracing as indicated at 52 may be advisable to transmit the thrust of the digging operation to the traction wheels.

It will be evident, therefore, that the device accomplishes its objects. The shovel 11 may be manipulated for gathering and 15 for elevating the load. Such elevation may be just enough to transport the load to another locality or the shovel may be raised to any desired height by extending the telescoping column through proper operation of the cables 9 and 10. The position of the shovel may be adjusted as desired either 20 before or during elevation or when elevated. After elevating the column, the load may be swung to either side so that it is unnecessary 25 to move the tractor body in order to adjust the shovel over the conveyance which is to receive the load. The manipulative controls are all located within easy reach of the driver who is the sole operator of the 30 machine.

It is obvious that various changes may be made in details of construction without departing from the spirit of this invention; it is, therefore, to be understood that this invention is not to be limited to the specific 35 details shown and described.

Having thus described the invention, what is claimed is:

1. A machine of the character described, 40 comprising, a power propelled frame, a shovel engaging with said frame and propelled thereby in order to fill the same, a derrick mounted for vertical movement on said frame, means for elevating said shovel 45 on said derrick, and means for elevating said derrick on said frame.

2. A machine of the character described comprising, a power propelled frame, a shovel engaging said frame and propelled thereby in order to fill the same, a column 55 mounted on said frame, a boom on said column, means on said boom for lifting said shovel, and means for lifting said boom.

3. A machine of the character described, 60 comprising, a power propelled frame, a shovel engaging said frame and propelled thereby in order to fill the same, a telescoping column mounted on said frame, means on said column for lifting said shovel, and means for extending said column.

4. A machine of the character described, 65 comprising, a power propelled frame, a shovel engaging said frame and propelled thereby in order to fill the same, a telescoping column mounted on said frame, means

on said column for lifting said shovel, and means engageable by said shovel to extend said column.

5. A machine of the character described, comprising, a power propelled frame, a shovel 70 engaging said frame and propelled thereby in order to fill the same, a telescoping column mounted on said frame, means on said column for lifting said shovel, and means within said column for extending the 75 same.

6. A machine of the character described comprising, a power propelled frame, a shovel 80 engaging with said frame and propelled thereby in order to fill the same, cables for suspending said shovel on said frame, means operating through said cables for elevating said shovel, means for swinging said shovel laterally, and means for adjusting said suspending cables relatively in order to tip 85 said shovel.

7. A machine of the character described comprising, a power propelled frame, a shovel 90 engaging with said frame and propelled thereby in order to fill the same, a derrick mounted for vertical movement on said frame, cables for suspending said shovel on said derrick, means operating through said cables for elevating said shovel, and means for adjusting said cables relatively 95 in order to tip said shovel.

8. A machine of the character described, comprising, a power propelled frame, a shovel engaging with said frame and propelled thereby in order to fill the same, a 100 derrick mounted for vertical movement on said frame, cables for suspending said shovel on said derrick, means operating through said cables for elevating said shovel, and means operating through said cables for 105 elevating said derrick.

9. A machine of the character described, comprising, a power propelled frame, a shovel 110 engaging with said frame and propelled thereby in order to fill the same, a telescoping column mounted on said frame, cables passing through said column for suspending said shovel therefrom, means operating through said cables for lifting said shovel, and means on said column and operated through said cables for extending said column.

10. A machine of the character described comprising, a power propelled frame, a shovel 115 engaging with said frame and propelled thereby in order to fill the same, a telescoping column mounted on said frame, cables for suspending said shovel from said column, and means operating through said cables adapted to lift said shovel and thereafter extend said column.

11. A machine of the character described comprising, a power propelled frame, a shovel 120 engaging with said frame and propelled thereby in order to fill the same, a

- telescoping column mounted on said frame, cables passing through said column for suspending said shovel therefrom, means operating through said cables for lifting
- 5 5 said shovel, means on said column and operated through said cables for extending said column, and means for adjusting said cables relatively to tip said shovel.
12. A machine of the character described comprising, a power propelled frame, a shovel engaging with said frame and propelled thereby in order to fill the same, a telescoping column mounted on said frame, cables for suspending said shovel from said
- 10 15 column, means operating through said cables adapted to lift said shovel, and an abutment on said column adapted for engagement by said shovel to extend said column.
12. A machine of the character described comprising, a power propelled frame, a shovel engaging with said frame and propelled thereby in order to fill the same, a telescoping column mounted on said frame,
- 20 25 cables for suspending said shovel from said column, means operating through said cables adapted to lift said shovel, an abutment on said column adapted for engagement by said shovel to extend said column,
- 30 and means for adjusting said cables relatively to tip said shovel.
14. A machine of the character described, comprising, a power propelled frame, a shovel engaging with said frame and propelled thereby in order to fill the same, a derrick mounted for vertical movement on said frame, means for elevating said shovel on said derrick, and means for moving said derrick to swing said shovel laterally.
- 35 40 45 15. A machine of the character described, comprising, a power propelled frame, a shovel engaging with said frame and propelled thereby in order to fill the same, a derrick mounted for vertical movement on said frame, means for elevating said shovel
- on said derrick, means for elevating said derrick, means for moving said derrick to swing said shovel laterally.
16. A machine of the character described comprising, a power propelled frame, a shovel engaging with said frame and propelled thereby in order to fill the same, a derrick mounted for vertical movement on said frame, means for elevating said shovel on said derrick and thereafter elevating said
- 50 55 60 65 70 75 80 85 90 95 derrick, and means for moving said derrick to swing said shovel laterally.
17. A machine of the character described comprising, a power propelled frame, a shovel engaging with said frame and propelled thereby in order to fill the same, a derrick mounted for vertical movement on said frame, means for elevating said shovel on said derrick and thereafter elevating said derrick, and means for moving said derrick while so elevated to swing said shovel laterally.
18. A machine of the character described comprising, a power propelled frame, a shovel engaging with said frame and propelled thereby in order to fill the same, a derrick mounted for vertical movement on said frame, means for elevating said shovel on said derrick, means for elevating said derrick, means for moving said derrick to swing said shovel laterally, and means for dumping said shovel.
19. A machine of the character described comprising, a power propelled frame, a shovel engaging with said frame and propelled thereby in order to fill the same, a derrick mounted for vertical movement on said frame, means for elevating said shovel on said derrick and thereafter elevating said derrick, means for moving said derrick while so elevated to swing said shovel laterally, and means for dumping said shovel.
- In testimony whereof I affix my signature this 8th day of October, 1923.
- WILLIAM R. GLASGOW.
